UNITED STATES PATENT OFFICE.

JOSEPH V. LANDRY, OF KILLONA, LOUISIANA.

OIL-BURNER.

1,300,626.

Specification of Letters Patent. Patented Apr. 15, 1919.

Application filed December 26, 1918. Serial No. 268,262.

To all whom it may concern:

Be it known that I, JOSEPH V. LANDRY, a citizen of the United States, residing at Killona, in the parish of St. Charles and State 5 of Louisiana, have invented certain new and useful Improvements in Oil-Burners, of which the following is a specification, reference being had to the accompanying drawings.

10 This invention relates to burners for vaporizing and burning crude oil and the general object of the invention is to provide a burner of this character which is very simple in construction, and which is very effective.

15 A further object is to provide a construction of this character in which the oil passing to the discharge nozzle of the burner is sub-divided and passes through a plurality 20 of heating pipes prior to its ejection from the burner so that the oil is vaporized before it is mixed with the steam and ejected.

25 A further object is to provide very simple means whereby the oil pipes may be cleaned or blown out.

Other objects will appear in the course of the following description.

30 My invention is illustrated in the accompanying drawings, wherein:—

Figure 1 is a vertical longitudinal sectional view of my oil burner; and

Fig. 2 is a section on the line 2—2 of Fig. 1.

35 Referring to these drawings, it will be seen that my improved oil burner comprises a steam chamber 10 which is illustrated as cylindrical in form and which is preferably formed of a main section and a head 11 bolted, riveted or otherwise attached to the 40 main section. This main section is formed with a nozzle 12 and into the steam chamber or chest extends the steam pipe 13 connected to a source of steam under pressure.

45 Extending through the head 11 opposite the nozzle 12 is an oil supply pipe 14 and disposed in the nozzle 12 is an oil discharge nozzle 15 which is on a line with the pipe 14. Connected to the inner ends of the pipe 14 and the nozzle 15 are the "crosses." Connecting the arms of the crosses 16 are the 50 pipes 17. It will thus be seen that the oil fed to the burner after it enters the steam chamber 10 is divided into a plurality of channels and passes through the relatively 55 small pipes 17 so that all of the oil is thoroughly heated and, as a consequence, vapor-

ized before it is discharged from the oil nozzle 15.

In order to provide means for cleaning the oil pipes 14, 15, 16 and 17 I provide a steam pipe 18 leading from the steam supply pipe 13 and entering the pipe 14. The main steam supply pipe 13 is provided with a valve 19 between the steam chamber and the junction of the pipe 18 and this pipe 18 is 60 provided with a valve 20 and also with a valve 21 adjacent the oil pipe 14. This oil pipe is also provided with a valve 22 for controlling the flow of oil to the pipes 17 and the bottom of the chamber 10 has a 65 drainage opening controlled by a cock 23 for removing water from the chamber.

In the operation of this device the valves 20 and 21 are closed and the valve 19 opened and the valve 32 opened. Oil therefore 75 passes into the pipes 17 while steam passes into the interior of the chamber and this steam is under relatively high pressure and its heat vaporizes the oil in the pipes 17. The steam discharges through the nozzle 80 12 and in doing so sucks out the vaporized oil through the oil nozzle 15 and ejects a stream of steam and vaporized oil from the nozzle 12 into the furnace with which the burner is used. If it be desired to clean the 85 burner the valves 19 and 22 are closed and the valves 20 and 21 are opened. This permits steam to pass through the pipe 18 and into and through the pipes 14, 17 and 15 and blowing out all foreign matter within these 90 pipes.

Inasmuch as the oil is divided into a plurality of streams while passing through the steam chamber, it will be thoroughly heated so that the final combustion is perfect. Before leaving the burner the oil is thoroughly 95 mixed with the discharging steam jet and leaves the burner in the form of a fine vapor which is ignited near the nozzle and which burns with a white flame. This burning jet 100 in practice has been found to extend far back into the furnace and even up into the flues.

This burner is particularly valuable where crude oil is being used, but is also capable 105 of being used with any form of oil. The burner may be made of various sizes but the nozzle of the burner is to have a depth equal to the thickness of the furnace wall.

I claim:—

1. An oil burner of the character described including a steam chamber adapted

110

to be connected to a source of steam under pressure and having a discharge nozzle, and an oil pipe entering the steam chamber and connecting with a plurality of relatively small pipes extending longitudinally through the steam chamber, and a single nozzle passing into the steam chamber nozzle and with which said plurality of pipes are connected.

- 10 2. An oil burner comprising a steam chamber having a steam supply pipe adapted to be connected to a source of steam under pressure, the steam chamber having a nozzle at one end, an oil supply pipe entering the rear 15 end of the steam chamber and connected to a plurality of radiating pipes, longitudinally extending pipes connecting to the radiating pipes and extending longitudinally of the steam chamber, an oil nozzle shorter than 20 and extending into the discharge nozzle of the chamber and connected to a plurality of radiating pipes at its inner end, to which

radiating pipes the longitudinal pipes are connected, and a valve controlling the pressure of steam within the chamber. 25

3. A burner of the character described including a steam chamber formed in two detachable sections and provided with a nozzle, a steam pipe entering the steam chamber, an oil supply pipe entering the rear end of 30 the chamber opposite the nozzle, an oil delivery nozzle extending partially into the steam nozzle, a plurality of pipes connecting the oil nozzle with the oil supply pipe, a branch pipe extending from the steam pipe 35 to the oil supply pipe and having valves adjacent the steam and oil supply pipes, and a drainage cock in the chamber.

In testimony whereof I hereunto affix my signature in the presence of two witnesses. 40

JOSEPH V. LANDRY.
